UNITED STATES PATENT OFFICE.

DELOS H. BUMPUS, OF EDENBURG, PENNSYLVANIA.

LUBRICATOR.

SPECIFICATION forming part of Letters Patent No. 233,323, dated October 19, 1880.

Application filed April 7, 1880. (No model.)

To all whom it may concern:

Be it known that I, DELOS H. BUMPUS, of 5
Edenburg, in the county of Clarion and State
of Pennsylvania, have invented certain new
and useful Improvements in Oil-Cups or Lu-
bricators; and I do hereby declare that the
following is a full, clear, and exact description
of the invention, which will enable others
skilled in the art to which it appertains to
make and use the same, reference being had
to the accompanying drawings, and to letters
of reference marked thereon, which form a
part of this specification.

Figure 1 is a vertical section of an improved
15 oil-cup, taken through 3 3 of Fig. 3, exhibiting
the oil-discharge shell at its highest position
and in communication with the oil-reser-
voir, part of the lever for operating being
shown on the left-hand side. Fig. 2 is a ver-
20 tical section of the same device, exhibiting
the oil-shell at its lowest position in communi-
cation with the lower discharge-bore, (which
may connect with an engine or pump,) with
the lever for operating the same shown in part
25 on the right-hand side. Fig. 3 is a cross-sec-
tion taken through lines 1 and 2 of Figs. 1
and 2, showing the lever in full in one position
and in dotted lines in another position.
Fig. 4 is an elevation of the stem and the per-
30 forations for receiving and discharging the
lubricants, also the screw-thread for operating
the oil-shell. It also shows, in section, the oil-
shell with its chamber in communication with
the steam-escape pipe.

35 The object of my invention is to provide a
lubricating-oil cup superior in mode of oper-
ating to those now used.

My invention consists of a reservoir, A, se-
cured to a stem, B, solid in the center at C,
40 and hollow at each end at D and D', which
hollow ends are provided with perforations d
and d'. The upper part, D, has also a steam-
escape pipe, E, which extends upward beyond
the mouth of the reservoir A.

45 On the center C of the stem B is the re-
cessed screw-thread F, extending about half-
way around it, for the reception of the lug J,
which forms part of the handle I for operating
the shell.

50 Surrounding the stem B is an oil-shell, G,

for receiving and discharging the oil. It is
provided with stuffing-boxes g and g' on each
end, which are provided with screw-caps h', and
made steam-tight by asbestos or other suitable
packing, (shown at i.) The shell G is mov- 55
able on the stem B by means of the handle I,
and the end J of the handle I, engaging in
the screw-thread F, causes the shell to rise or
fall on the stem B, and thus communication
from the chamber G' can at will be secured 60
with the upper or lower part, D or D', of the
stem B. The shell G is thrown upward in po-
sition, as shown in Fig. 1, to charge the cham- 65
ber G'; but before arriving at the oil-ports d
the confined steam, if any, in G' escapes through
the steam-escape pipe E, which is lower than
the perforations d', and by the time the shell
has reached its extreme height the steam has 70
all escaped, and then the oil runs from the
reservoir A through the ports d into the cham- 75
ber G'. The handle I is then thrown to its
second position, the lug J traverses the screw-
thread F, and the shell G is forced down
to the second position, as shown in Fig. 2.
The ports d and steam-pipe E are thus closed 80
and the ports d' opened, and the lubricant en-
ters the lower bore, D', through the perfora-
tions d' and flows out into the engine or pump.

With my improved oil-cup or lubricator
there is no inconvenience or trouble or loss of 85
time in mode of operation. A simple turn of
the lever in one direction throws the shell up
for receiving the lubricant, and a turn in the
opposite direction throws said chamber down
for depositing or discharging the lubricant. 90
The operation of my device is almost instant-
aneous, and there is no splashing of oil, as
all the confined steam escapes from the steam-
escape pipe E, and does not throw out the oil
from the reservoir A.

What I claim as new, and desire to secure
by Letters Patent, is—

1. An oil-cup or lubricator consisting, es-
sentially, of a movable oil-chamber, which may
at will be placed in communication with ports 95
from an oil-reservoir, or with ports to the ma-
chine to be lubricated, substantially as shown
and described.

2. An oil-cup or lubricator consisting of a
suitable reservoir connected by suitable ports 100

to a movable oil-chamber, which, by a single motion of a handle, will close one set of ports and open another, substantially as shown and described.

5 3. In an oil-lubricator, the steam-escapes E, as shown and described, and for the purpose specified.

4. In an oil-cup or lubricator, the combination of the reservoir A, its stem and ports,

with the movable shell G, substantially as 10 shown and described.

In testimony that I claim the foregoing as my own I affix my signature in presence of two witnesses.

DELOS HENRY BUMPUS.
